UNITED STATES PATENT OFFICE.

PAULA KLEIN, OF NEW YORK, N. Y.

BANDAGE-CORSET.

1,107,078.

Specification of Letters Patent. Patented Aug. 11, 1914.

Application filed September 6, 1913. Serial No. 788,401.

To all whom it may concern:

Be it known that I, PAULA KLEIN, a citizen of the United States, and a resident of the city of New York, borough of Manhattan, in the county and State of New York, have invented a new and Improved Bandage-Corset, of which the following is a full, clear, and exact description.

This invention relates to a corset construction and more particularly to a bandage corset, the object of the invention being to provide an attachment which is applicable to corsets of general construction and designed for use by women after operations and for maternity uses so as to support the lower part of the abdomen and provide for increased comfort by avoiding all downward pressure and relieving and curing symptoms due to relaxed and inefficient abdominal walls.

A further object of the invention is to provide a corset of the nature described which embodies an adjustable section so as to provide a range of adjustment adapted for different persons and in which a substantially lenticular or oval engaging part is designed to conform to the body of the wearer and be held against movement during the supporting action.

With the above and other objects in view the invention resides more particularly in the peculiar combination and arrangement of parts which will be illustrated as a preferred embodiment in the accompanying drawings and described in the specification.

Reference is to be had to the accompanying drawings forming a part of this specification, in which similar characters of reference indicate corresponding parts in all the views, and in which—

Figure 1 is a front elevation of a bandage corset constructed in accordance with the invention; Fig. 2 is a fragmentary inside elevation showing the supporting section; and Fig. 3 is a cross sectional view taken on the line 3—3 of Fig. 2 with the parts straightened out.

In the drawings, the numeral 10 designates a pair of corsets the sections of which are laced at the back in the usual manner, as indicated by the numeral 11, so as to

provide the usual range of adjustment, while the front portions thereof are connected by the usual fasteners 12. The sections are also provided with the side stocking supporters 13 and the central supporters 14, each being capable of adjustment in the usual manner.

In the application of the invention to the device as above described, each section of the corset adjacent the sides of the body is provided with a substantially vertical reinforcing strip 15 the two converging upwardly and being designed for securely attaching a plurality of, preferably five, vertically spaced and upwardly converging rows of eyelets 16. A supporting section 17 which is of substantially lenticular or oval shape or consists of a section tapering toward its ends, with convexly arcuate top and bottom edges and upwardly converging straight side edges 19, as shown in Fig. 2 of the drawings, is provided to support the abdomen and for this purpose is provided with a surrounding reinforcing edge or binding 18, and straight side edges 19 to which are connected a plurality of non-elastic tapes 20, it being observed that said edges 19 are substantially parallel to the direction of extent of the eyelets 16.

The supporting section 17 is in its general nature flexible, and so shaped as to conform to the body of the wearer to provide increased supporting action and comfort, said section at or near its ends being provided with a plurality of upwardly diverging flexible stiffeners 21, preferably of bone, and at spaced points intermediate thereof with vertical stiffeners 22 of similar form, thus causing said section to comfortably fit the abdomen. The tapes 20 are extended outwardly in spaced relation through the eyelets 16 and carried back toward the front edges of the corset where they are connected to non-elastic sections 23 in such manner as to bring the tapes 20 in substantially convergent relation. These portions 23 are adjustably connected through the instrumentality of an inelastic tape section 24 carrying a buckle 25 at its free end and an inelastic tape section 26 designed to adjustably engage the buckle and of sufficient length to permit a range of adjustment up to ten

inches. The section 23 carrying the buckle attaching section 24 is provided with a loop 27 to receive the free end of the engaging section 26 so as to retain the parts in a flat 5 condition and thereby prevent bulging or discomfort when being worn.

Near the central part of the lower edge of the supporting section 17 are provided depending adjustable supporters 28 constructed of elastic material in the usual manner, and these sections are passed through reinforced horizontally alined spaced slots or openings 29 in the corset sections at each side of the adjoining front 15 edges. By this means, when the supporters are attached to the stockings the supporting section 17 is held from movement upwardly to become displaced and in addition, the supporting action of the adjustable member including the tapes 20, also prevents said section 17 from moving downwardly so as to support the abdomen with extreme comfort. By reason of the engagement of the supporting section with the inner faces of the 25 corset sections at the front, downward movement of the supporters together with the supporting section, beyond a predetermined degree, is prevented in such a manner as to serve a double function by simultaneously holding the flexible lower part of the corset 30 and the supporting section inward and in supporting position.

In the use and application of the improvement with the corset, the sections are laced 35 at the back so as to be comfortably tight when fastened in the front. The corset is put on like a pair of drawers, while the front is unfastened and before the ends of the tape sections 24 and 26 are connected, the 40 wearer passing the legs through at the top so that the bandage section 17 will lie in front of the lower part of the abdomen. The bandage or supporting section 17 is then fitted under the abdomen to properly support the same, and after the corset is fastened thereover, the tape sections 24 and 26 are connected and drawn taut. As the corset fits the body it will not be bunched when the tape sections 24 and 26 are connected to 45 bind the bandage section 17. This is due to the fact that the eyelets 16 are positioned at the sides of the body and the body will not be reduced to any appreciable degree. The supporters will also tend to pull downwardly on the flexible lower part of the 50 corset and assist in retaining the same smooth and prevent crowding or bunching of the parts toward the center.

Having thus described my invention, what 60 I claim as new and desire to secure by Letters Patent is:—

1. The combination with corset sections; of a substantially oval and reinforced supporting section at the inner side thereof, ad-

justable connections carried by the ends of 65 said supporting sections, extended through the corset sections and connected at the front, and depending supporters carried by said supporting section, said corset sections having horizontally alined openings 70 through which said supporters extend.

2. The combination with corset sections having a plurality of spaced openings at the side portions; of an abdominal supporting section provided with flexible reinforcing members designed to conform to the body, tapes connected to the extremities of said supporting sections and passing through the openings, and inelastic and adjustable connections between the free extremities of the tapes exteriorly of the corset, the sections having openings near their joining front edges and elastic supporting members connected to the lower edge of the abdominal supporting section and movably 85 engaged through said openings against limited downward displacement.

3. The combination with corset sections proper having connecting means at the front and back; of a substantially lenticular reinforced supporting section loosely mounted at the inner side thereof and adapted for adjustment independent of the corset sections in front of the abdomen, adjustable connections carried by the ends of said supporting section, said connections being extended through the corset sections proper and toward each other at the front and connected, and depending supporters carried by 90 said supporting section and engaged with the corset sections to hold the supporting section against upward movement and simultaneously hold the lower portions of the corset sections and supporting section 95 in supporting position.

4. The combination with corset sections having flexible lower portions and reinforcements in the sides thereof converging upwardly and provided with vertical rows of eyelets mounted therein; of a supporting section adapted for adjustment independent of the corset sections and having flexible reinforcing stays permitting the supporting section to conform to the body, said supporting section also having convexly arcuate top and bottom edges and upwardly converging straight side edges, a plurality of inelastic tapes attached to said supporting section at spaced points of the sides of the latter and extending through the eyelets in spaced parallel relation, said tapes being carried straight toward the front edges of the sections, inelastic sections connected to the tapes, adjustable buckle connections between the inelastic sections whereby pull exerted thereon will tend to straighten the supporting section between the eyelets through which the tapes extend and cause 100 105 110 115 120 125

the same to be tightened against the body, and means at the central portion of the supporting section to simultaneously hold the lower portions of the corset sections and the supporting section inward in supporting position and limit the upward and downward displacement of said supporting section.

In testimony whereof I have signed my name to this specification in the presence of two subscribing witnesses.

PAULA KLEIN.
